(57) **CLAIM**

The ornamental design for a headset as shown and described.

DESCRIPTION

FIG. 1 is a front perspective view of the headset comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

Broken lines shown in the drawings illustrate portions of the headset and form no part of the claimed design. The headset is shown with a symbolic break line between the headset and headset controller in FIGS. 1–5 and 7–8; the appearance of any portion of the article between the break lines form no part of the claimed design.
